UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed March 20, 1924. Serial No. 700,460.

The invention is in the nature of an improvement on Patent No. 1,414,738, granted to me May 2, 1922, in which a light spring tends constantly to throw a back-spacing dog into mesh with the carriage-rack. Said meshing spring must be overcome by the tension of a second spring, the latter serving to restore the back-spacing devices to normal positions when the key is released; 5 it being part of the duty of said returning spring to disconnect said back-spacer dog from the carriage-rack in opposition to the tension of the first-mentioned spring.

It is found in practice that considerable 15 close fitting and adjustment is required in order to insure correct action of the back-spacing mechanism, since the tension of the meshing spring must be sufficient for positively interengaging the pawl with the carriage-rack at the start of the depression of the back-spacing key, whereas said meshing spring must be weaker than said returning spring, so that the latter may promptly disconnect the pawl from the carriage-rack. 20 Moreover, there is liability of the mechanism being put out of order by attempts of untrained workers to adjust the relative tension of said springs.

An object of the invention therefore is 30 to avoid the necessity of opposing one spring by another in the manner stated, to simplify the mechanism, to reduce the difficulty and expense of assembling the parts, and to overcome liability of trouble arising from bungling attempts to readjust the tension.

One of the features of the improvement consists in causing a single spring to take the place of two opposing springs; and to 40 this end a new spring is provided, which has a variety of actions and functions. The new spring is anchored upon an extended portion of the connecting link forming part of the back-spacing mechanism, so that said spring is capable of exerting upward pressure. The new spring co-operates with the back-spacing key to pull forward the back-spacer pawl into preliminary mesh or engagement with the carriage-rack.

50 Other features and advantages will hereinafter appear.

In the accompanying drawings,

Figure 1 is a diagrammatic side view, looking from right to left in Figure 2, partly in section, illustrating my invention as

applied to an Underwood typewriting machine.

Figure 2 is a fragmentary front view, showing the back-spacing pawl in its normal position.

Figure 3 is a plan, partly in section, of the lower end of the connecting rod or pitman, showing parts connected thereto.

11 designates the platen of the machine, which is movably supported by a carriage 65 12, which slides on rails 13 and 14, and has connected to the under side thereof a back-spacing rack 15 by means of arms 16.

Key-levers 17 are shown as pivotally connected to a bridge 18 at the rear of the 70 machine by means of a rod 19, and are supported in their normal position by compression-springs 20. A second bridge 21, situated forwardly of said bridge 18, has bell-cranks 22 pivotally connected thereto 75 by means of a rod 23.

A back-spacing key 24 is mounted at the front end of a back-spacing key-lever 25, which is secured to a rock-shaft 26 at the left end thereof. Said rock-shaft 26 has 80 secured thereto, at the right end thereof, an arm 27, which is pivotally connected to a short extension 28 at the lower end of a connecting rod or pitman 29, forwardly thereof, by means of a pin 30.

The lower end of the pitman 29 has thereon also a spur 31, rearwardly of said extension 28, which terminates in a bend 33 at right angles thereto, which bend is shown as having anchored thereto the lower end 90 of a restoring spring 32, the upper end of which is shown as connected to a bracket 34 at the front of said bridge 18. The spring 32 is preferably substantially vertical and initially strained. The upper end of the pitman 29 is pivotally connected at 95 35 to a substantially horizontal arm 36 of a back-spacing pawl 37, which is pivotally connected at 38 to the main back-spacing lever or pawl-carrier 39, which is pivotally connected at 40 to a stationary part of the machine, to swing in a plane parallel to the key-lever 25 and arm 27.

The pawl 37 is situated in a substantially vertical plane transversely to the plane of the lever 39, which is provided with a stop 41 thereon to limit the swinging of the pawl 37 to the left in Figure 2. The pawl 37 also has at the lower end thereof a spur 42 normally situated at a short distance from 100 43.

the right side of the lever 39 to limit the swinging of the pawl 37 with its upper end to the right in Figure 2, thereby limiting the extent of back-spacing.

5 The lever 39 with the pawl 37 is normally kept inclined rearwardly, with a tooth 43 of the pawl 37 out of mesh with the rack 15, by the upward pressure of the pitman 29 produced by the tensile course of the spring 32 exerted on the lower end of said pitman, which accordingly tends to drive the lever 39 to the right, or at least to restrain it from turning to the left. At Figure 1 the pitman 29 and lever 39 form a nearly closed toggle. The upper end of the lever 39 normally leans against the neck of a stud 44, which is secured to a stationary part of the machine, leaving a small space between the front of the upper end of said lever 39 and 15 the rear of the rack 15.

10 20 When the key-lever 25 is being depressed, the arm 27 pulls downwardly on the extension 28 of the pitman 29 by means of the pin 30. The spring 32, which is under tension, at such downward pull helps to turn the pitman 29 forwardly about pivot 30, thereby swinging the lever 39 with the pawl 37 thereon forwardly thus opening the nearly closed toggle until the upper end of 25 the lever 39 is stopped by the rear of the rack 15, or by the inner side of a hooked projection 45 at the rear of said lever 39 against the rear of said stud 44.

30 35 This swinging of the lever 39 forwardly brings the pawl 37 with its tooth 43 into mesh with the teeth on the under side of the rack 15 before the pawl 37 is turned in its own plane by the continued action of the pitman 29 thereon, as hereinafter described.

40 45 When the above-described turning of the pitman 29 is discontinued, through the stopping of the swinging of the lever 39, the continued downward pull of the arm 27 on the lower end of the pitman 29 stretches the spring 32 and moves said pitman 29 downwardly. The upper end of the pitman then acts on the substantially horizontal arm 36 of the pawl 37 and turns the latter in a clockwise direction in Figure 2, thereby moving the rack to the right until the pawl 37 is stopped when the spur 42 thereof is 50 55 encountered by the right side of the lever 39, thereby completing one stroke of back-spacing.

60 65 When the key-lever 25 is released, the spring 32 lifts the pitman 29, which is then prevented by the pawl-and-ratchet mechanism 46, 47 (shown in Figure 2) from turning the pawl 37 in a counterclockwise direction, while its tooth 43 is in mesh with the rack 15. The upward pressure of the pitman 29, therefore, swings the lever 39 with the pawl 37 thereon backwardly to the original toggle-closing position of said lever 39, 65 70 thereby bringing the tooth 43 of said pawl

70 75 75 80 85 90 95 100 105 110 115 120 125 130 37 out of mesh with the rack 15; whereupon the continued upward pressure of the spring and pitman 29 turns the pawl 37 on its pivot in a counterclockwise direction in Figure 2, until it is intercepted by the stop 41 on the lever 39, thereby bringing the pawl 37 to its original position, when the back-spacing mechanism is again in its initial state and prepared for another four-motion back-spacing cycle.

By the above simple expedients of having the pin 30 at the lower end of the pitman 29 situated at a distance 29^a from its connection with the lower end of the spring 32, forwardly thereof, and by having said spring initially strained, the initial depression of pivot 30 permits the tensioned spring 32 to open the toggle, i. e., the pitman is caused to swing the lever 39 with the pawl 37 thereon forwardly, thereby bringing the tooth 43 of the pawl 37 into mesh with the rack 15 before said pawl is turned in its plane for back-spacing by the continued action of the pitman thereon. So long as pivot 30 is held up by the spring the latter cannot open the toggle, but when said pivot 30 is initially depressed by the key 24, said spring instantly opens the toggle i. e., swings pitman 29 forwardly, thus vibrating lever 39 forwardly.

The extra spring, heretofore employed with the lever 39, as above described, is thereby rendered superfluous, and is, therefore, eliminated, together with the labor of fitting it into position in the machine.

It will be understood that at the downward start of the key-lever 25, the pivot 30 descends, thereby tending to operate through link 29 to pull the unit (comprising 39 and 37) forwardly around pivot 40. This tendency of said unit to swing around 40 is substantially aided by the spring 32. Said spring 32, regarded in one way, is in the nature of a fulcrum for an elbow-lever comprising the long arm 29 and the short arm 29^a, so that the downward movement of the free forward end of the short arm tends to swing forwardly the upper end of long arm 29. During this forward swing of said unit 39, 37, and the consequent engagement of the tooth or dog 43 with the carriage-rack 15, there is no significant downward movement at 31 or 33, on account of the resistance offered by the spring 32. It is also noted that the liability of the dog 43 being prematurely swung about the pivot 38, at the start of the down stroke of the key, is overcome by the resistance which the spring 32 offers to a vertical downward movement of the link or pitman 29. It is easier for the unit comprising 39, 37 to swing forwardly about the pivot 40 (thus engaging the dog with the rack) than it is for the link 29 to descend in opposition to the resistance offered by the spring 32. Hence at

the start of a key the dog 43 swings forwardly around pivot 40 into mesh with the rack, and, on further descent of the key, the dog 43 is forced to swing around pivot 38, 5 thereby back-spacing the carriage. Upon relief of the key from pressure, the spring 32 has the effect of thrusting up the link or pitman 29 and causing it to swing the unit 39, 37 backwardly about the pivot 40, 10 until the dog 43 escapes from the rack, inasmuch as it is easier for the dog to move in this direction than it would be to force its way in a direction endwise of the rack. When the dog has escaped from the rack, 15 the spring 32 through link 29 swings the dog about pivot 38 and completes the return of all the other parts to normal positions.

The connecting link 29 is under constant tension to turn around pivot 30 in forward direction, by reason of spring 32, but, on account of greater pressure upward exerted by spring 32, said link 29 tends to turn 39 to the right, and thereby the link is restrained from turning to the left or forwardly, and hence the forward action of the link does not take place until the back-spacer key-lever is depressed.

The forward action of the back-spacer pawl 37 and carrier 39 around pivot 40 is principally due to the fact that when depressing the back-spacer key-lever 25, the upward pressure of the spring 32 is counteracted and the pivot 30 is depressed, so that the forward pressure of the spring on the 35 link is permitted to swing the lever 39 and the pawl to engage in the spacing rack instantaneously.

In the normal position at Figure 1, the linkage 29, 39 forms a nearly closed toggle 40 which is self-locking, because the pivot 30, at one end of said linkage, is held up by the spring 32. The link 29 cannot be swung to the left by spring 32, because the upper end of said link 29 would have to swing upwardly as well as forwardly around pivot 30, whereas the pivot 35 (where 29 is attached at its upper end) would have to swing downwardly as well as forwardly about pivot 40. The tendency to upward movement of link 29 around pivot 30 would be resisted by the tendency to downward movement of 39 around pivot 40. The point 38 cannot move in two divergent arcs, one about pivot 30 and the other about pivot 40. Pivot 30 must move down in order to enable pivot 35 to swing forward and down. Spring 32 prevents 30 from moving down, until the spring is overcome by pressure on the key 24.

Variations may be resorted to within the scope of the invention, and portions of the improvements may be used without others.

Having thus described my invention, I claim:

1. In a typewriting machine, the combina-

tion of a platen, a carriage for movably supporting the same, and means for back-spacing said carriage, said means comprising a rack connected to said carriage, a back-spacing lever pivotally mounted to 70 swing in a vertical plane transversely to the rack, means for stopping the forward swinging of the lever, a pawl pivotally connected to said lever and carriage thereby, to swing in a substantially vertical plane transversely 75 to the plane of said lever, a tooth on said pawl to engage said rack, said lever normally keeping said pawl out of mesh with said rack, a pitman pivotally connected at the upper end thereof to said pawl and, 80 through said pawl, to said lever, and a spring supported at one end thereof and connected at the other end thereof to the pitman, combined with means to be applied for drawing said pitman, substantially 85 downwardly, the point of application of said drawing means being situated forwardly of the connection of said spring to said pitman, with a space therebetween, the forces of said spring at said pitman and 90 of said drawing means with said space therebetween thereby forming a couple to turn said pitman in a plane parallel to said lever, swinging said lever forwardly, and bringing said pawl into mesh with said rack until 95 said lever is intercepted by said stopping means, and the continued application of said drawing means to said pitman thereupon to turn said pawl in its plane, thereby moving the rack for back-spacing the carriage. 100

2. In a typewriting machine having a carriage and a rack, a back-spacing mechanism for the carriage comprising a key-operated lever, a link extending therefrom, a back-spacing dog movable by said link first 105 laterally into mesh with said rack and then in a direction longitudinal of the rack to back-space the carriage, and a single spring connected to said link to tend to co-operate with the key to shift the dog into mesh with the rack at the start of the depression of the back-spacer key, and to return all the parts to normal positions at the relief of the key from pressure, said link being in the form of an elbow-lever, one arm of the elbow-lever being connected to the key-lever and the other arm being connected to the back-spacing dog to shift it into mesh with the rack, and said spring connected to the elbow to serve as a yielding fulcrum for 115 said lever to co-operate therewith in shifting the dog at the beginning of the key-stroke. 120

3. In a typewriting machine having a carriage and a rack, a back-spacing mechanism for the carriage comprising a key-operated lever, a link extending therefrom, a back-spacing dog movable by said link first laterally into mesh with said rack and then in a direction longitudinal of the rack 125 130

to back-space the carriage, and a single spring connected to said link to tend to co-operate with the key to shift the dog into mesh with the rack at the start of the depression of the back-spacer key, and effective to return all the parts to normal positions at the relief of the key from pressure, said back-spacing dog being mounted upon a rocker, and said link being pivoted to the dog for shifting the dog laterally bodily together with the rocker, means limiting such movement of the rocker, said spring also effective to turn the dog upon its own pivot; said spring being also effective upon relief of the key from pressure first to swing the dog and rocker to unmesh the dog from the rack, and then to swing the dog upon its own pivot to normal position.

4. In a typewriting machine having a letter-feeding carriage provided with a rack and a back-check device therefor, the combination of a back-spacing key and a four-motion back-spacing mechanism controlled by said key and including a pivoted back-spacing pawl normally out of engagement with said rack, a lever whereon said pawl is mounted, said lever pivoted to vibrate in a plane at right angles to said rack, and said pawl mounted to vibrate in a plane parallel with said rack, a four-motion link pivoted at one end to said pawl and capable of swinging the lever to carry the pawl bodily into and out of mesh with the rack, and also capable of vibrating the pawl independently of said lever to back-space the rack, and of restoring the pawl when free from the rack, a lever arm operable by said key and pivoted to the other end of said link, and a spring connected to said link and maintaining the lever arm, link, pawl and pawl-lever in normal positions, said link having a cross-arm engaged by said spring between the pivot of the lever arm and the point of pivotal connection of the link to the lever arm.

restoring the pawl when free from the rack, a lever arm operable by said key and pivoted to the other end of said link, and a single spring connected to said link to swing the link about its pivotal connection to said lever arm, and maintaining the lever arm, link, pawl and pawl-lever in normal positions.

5. In a typewriting machine having a letter-feeding carriage provided with a rack and a back-check device therefor, the combination of a back-spacing key and a four-motion back-spacing mechanism controlled by said key and including a pivoted back-spacing pawl normally out of engagement with said rack, a lever whereon said pawl is mounted, said lever pivoted to vibrate in a plane at right angles to said rack, and said pawl mounted to vibrate in a plane parallel with said rack, a four-motion link pivoted at one end to said pawl and capable of swinging the lever to carry the pawl bodily into and out of mesh with the rack, and also capable of vibrating the pawl independently of said lever to back-space the rack, and of restoring the pawl when free from the rack, a lever arm operable by said key and pivoted to the other end of said link, and a spring connected to said link and maintaining the lever arm, link, pawl and pawl-lever in normal positions, said link having a cross-arm engaged by said spring between the pivot of the lever arm and the point of pivotal connection of the link to the lever arm.

WILLIAM F. HELMOND.
